Primary Examiner — Prabhakar Deshmukh(74) *Attorney, Agent, or Firm* — Michael Best & Friedrich LLP**(57) CLAIM**

The ornamental design for a target for multiple toss games, as shown and described.

DESCRIPTION

FIG. 1 is an exploded perspective view of a target for multiple toss games showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a perspective view thereof, shown in an assembled position;

FIG. 7 is an exploded perspective view of a second embodiment of target for multiple toss games;

FIG. 8 is a top plan view of FIG. 7;

FIG. 9 is a front elevational view of FIG. 7; and,

FIG. 10 is a perspective view of FIG. 7, shown in an assembled position.

The shade lines define the boundary of the claimed design. The broken lines in the drawing are for illustrative purpose only and form no part of the claimed design.
